DESIGN FOR A FOOTED CASSEROLE OR SIMILAR ARTICLE

Harry I. Kleinberg, Pittsburgh, Pa.

Application February 12, 1944, Serial No. 112,548

Term of patent 14 years

(Cl. D36—2)

To all whom it may concern:

Be it known that I, Harry I. Kleinberg, a citizen of the United States, residing at Pittsburgh, in the county of Allegheny and State of Pennsylvania, have invented a new, original, and ornamental Design for a Footed Casserole or Similar Article, of which the following is a specification, reference being had to the accompanying drawing, forming a part thereof.

of the handle side of the footed casserole.

I claim:

The ornamental design for a footed casserole or similar article, as shown.

HARRY I. KLEINBERG.
